UNITED STATES PATENT OFFICE.

EARL C. HANSON, OF LOS ANGELES, CALIFORNIA, ASSIGNOR TO TITLE INSURANCE AND TRUST COMPANY, A CORPORATION OF CALIFORNIA.

AUDIOFREQUENCY WIRELESS FOG-SIGNAL SYSTEM.

1,388,949.

Specification of Letters Patent. Patented Aug. 30, 1921.

Application filed June 4, 1918. Serial No. 238,111.

To all whom it may concern:

Be it known that I, EARL C. HANSON, a citizen of the United States, residing at Los Angeles, in the county of Los Angeles and 5 State of California, have invented a new and useful Audiofrequency Wireless Fog-Signal System, of which the following is a specification.

My invention relates to the art of navigation, and the principal object of my invention is to provide means for indicating to a navigator the position of his ship with relation to other ships or natural objects. By 0 the use of my invention it is possible to navigate in heavy fogs. It is further possible to bring ships through tortuous channels into harbor without the use of light houses or other visible signals and with a high factor of safety.

0 Referring to the drawings, which are for illustrative purposes only—

Figure 1 is a side view of a ship in combination with one embodiment of my invention.

5 Fig. 2 is a section taken on a plane indicated by the line 2—2, Fig. 1, this plane being viewed in the direction of the arrow.

Fig. 3 is a diagram of what may be called the radiating apparatus.

0 Fig. 4 is a diagram of what may be called the receiving apparatus.

In the embodiment of my invention illustrated in these drawings, a ship 11 is shown, this ship floating on the surface 12 of the 5 ocean or other body of water. For the purpose of indicating to those on the ship the position of the ship with relation to natural objects I employ a pair of submarine cables 13 and 14. These cables are shown sup-

0 ported on floats 15 which are anchored by cables 16 to weights 17, the purpose of the floats being to maintain the cables 13 and 14 at an approximately definite depth "A" below the surface 12. The cables 13 and 14 5 may be placed in the relative position shown in Fig. 2 or they may be widely separated.

The cables 13 and 14 are heavily insulated so that they make no electrical contact 0 with the water in which they are submerged, and these cables are run to a convenient point on shore at which point are located a high frequency generator 20 and a low frequency generator 21, these generators operating at audio frequencies, that

is to say, at frequencies below 10,000 cycles per second, but at frequencies sufficiently different from each other to allow the difference to be readily detected, as will hereinafter be explained. Each of the generators is connected to the primary 22 of a transformer 23 having an iron core, these transformers having secondaries 24 and 25, one terminal of which is connected to ground as shown at 26, the other terminal 60 being connected to one of the cables 13 or 14, which in effect form antennæ, as shown.

Located on the ship and preferably surrounding it on the sides is an antenna 30. This antenna may be insulated and submerged but is preferably looped around the side of the ship and connected to the primary 31 of a receiving transformer 32 having an iron core, one terminal of the primary 31 being grounded at 33, the other terminal 70 being connected to the antenna 30. The secondary 34 of the transformer 32 has one terminal connected to a grid 35 of a vacuum bulb repeater 36, the vacuum bulb repeater 36 having a filament 37 energized by a filament battery 38. The filament 37 is also connected through a wire 39 with one terminal of the secondary 34 and with one terminal of a battery 40. The other terminal 75 of the battery 40 is connected through a milli-ammeter 41, a telephone receiver 42 and a pair of vibrating magnets 43 and 44 with a plate 45 in the vacuum bulb repeater 36. The magnets 43 and 44 are provided with iron cores which act upon vibrating reeds 46 and 47. Each of these vibrating reeds is so placed as to make contact through a battery 48 and a lamp 49 when rapidly vibrating.

The method of operation of the invention 95 above described is as follows:

The generators 20 and 21 are in continuous operation at all times when it is desired to utilize the invention and they impress an electro-static charge between the ground and the submerged wires 13 and 14. This electro-static charge sets up an electro-static field which includes the antenna 30 causing a current to flow through the primary 31 to the ground. This current induces a potential in the secondary 34 which controls a much heavier current passing from the plate 45 to the filament 37 in the vacuum bulb repeater 36, this heavy current also passing through the vibrating magnets 43 105 110

and 44, the telephone receiver 42 and the ammeter 41. The frequency of this current will depend upon which of the wires 13 and 14 the ship is closest to. In the position 5 shown in Fig. 2 there will be two superimposed frequencies flowing through the vibrating magnets 43 and 44, one of these being due to the generator 20 and the other being due to the generator 21. As a result 10 both the reed 46 and the reed 47 will vibrate and both of the lights 49 will be lighted. At the same time a musical note based on two frequencies will be heard in the receiver 42 and the relative strength of 15 the current flowing can be observed on the ammeter 41. The navigator will, therefore, know that he is close to both of the wires, and if the ammeter 41 is suitably calibrated 20 he will know very closely his distance from these wires.

As the vessel 11 recedes from either of the wires 13 or 14 the strength of the induced current produced by that wire through the ammeter 41, for example, will decrease and 25 at the same time the musical note corresponding to that frequency will become relatively less. Should the ship cross over either of the wires entirely so that it were on the opposite side, the navigator would practically hear only one note and the ammeter would indicate the distance from that wire. It will be seen that the submerged wires 13 and 14 would, therefore, form what might 30 be termed a lane which the navigator would have no difficulty in following by a proper 35 observation of the ammeter 41 and the lights 49, the proper position of the ship being between the wires 13 and 14 in which position both notes would be heard at about equal 40 loudness. These notes would be heard regardless of fog or other conditions and the indications would not be interfered with by radio waves or by other audio waves from sources located at a distance from the wires 45 13 and 14. The radio waves would be entirely ironed out by the iron core of the transformer 32 and inductive interference from power transmission lines on shore would be negligible.

50 In some cases the wires 13 and 14 might be placed on the shore and might serve not as signals to be followed but as warning signals, the visible signal given by the lights 49 or the audible signal given by the telephone receiver 42 being heard only as the ship approaches a dangerous position near the shore. By the use of my invention it would be possible by running a warning signal wire along a dangerous coast to effectively 55 warn ships which approach that coast even in dense fogs or under other conditions which would render visible signals uncertain and unreliable.

I claim as my invention:

1. In a system of navigation, the combination of a submerged cable energized from an audio-frequency source and apparatus on shipboard comprising a collector of the field of force emanating from the cable, a vacuum tube amplifier associated with said collector, and means for observing the received energy. 65
2. In a system of navigation, the combination of a submerged cable arranged along a channel and energized from an audio-frequency source, a collector system arranged on shipboard and adapted to be affected by the energy received from the cable, a vacuum tube amplifier associated with said collector system, and a visible indicator actuated by the received energy. 75
3. In a system of navigation, the combination of a submerged cable arranged in a ship channel and energized by a source of audio-frequency energy, and an apparatus on ship board affected by the field of force emanating from said cable, said apparatus comprising a collector system, a vacuum tube amplifier associated with said collector system, and visible and audible signals actuated by 80 said amplified energy. 90
4. In a system of navigation the combination of a submerged cable arranged in a channel and energized by a source of audio-frequency electric energy, and apparatus on shipboard comprising a collector system, a vacuum tube amplifier associated therewith, and means for visibly and audibly indicating the relative position of the ship to the cable. 95
5. In a system of navigation, the combination with a plurality of cables arranged in a channel, and energized by sources of different audio-frequency, of apparatus on shipboard comprising a collector system, a vacuum tube amplifier associated with said collector system, and visible indicators selectively actuated by the received energy in accordance with the relative position of the ship to said cables. 100
6. In a system of navigation, the combination of a submerged cable arranged in a channel and energized by a source of audio-frequency energy, with apparatus on shipboard comprising a collector system, a vacuum tube amplifier having its input circuit inductively coupled with said collector system, and an indicating instrument arranged in the output circuit thereof and calibrated to show maximum response when the distance between the collector system and the cable 110 is a minimum. 115

In testimony whereof, I have hereunto set my hand at Washington, D. C., this 4th day of June, 1918.

EARL C. HANSON.
